Attest:

UNITED STATES PATENT OFFICE.

CHARLES REDECKER, OF LOUISVILLE, KENTUCKY, ASSIGNOR OF ONE-HALF TO ROBERT V. BOARD, OF LOUISVILLE, KENTUCKY.

DOOR CONSTRUCTION FOR CONVERTIBLE AUTOMOBILE-BODIES.

1,269,307.

Specification of Letters Patent. Patented June 11, 1918.

Application filed November 25, 1916. Serial No. 133,401.

To all whom it may concern:

Be it known that I, CHARLES REDECKER, a citizen of the United States, residing at Louisville, in the county of Jefferson and

5 State of Kentucky, have invented certain new and useful Improvements in Door Constructions for Convertible Automobile-Bodies, of which the following is a specification.

10 This invention relates in general to automobiles of the convertible body type, and more particularly has special reference to a novel and practical improvement in door construction for use on bodies of the character set forth.

To this end the invention contemplates a construction wherein a panel or sash may readily be fitted to and removed from the usual swing door when desired to either 20 provide an inclosed or open body without the use of uprights or posts, which would otherwise be in the way when the side panels were removed. In the case of side panels which occupy a more or less permanent relation to the top and sides of the body, the 25 manner of holding the same in place is a relatively simple matter. However, difficulty is encountered when these panels are mounted on the tops of the swinging doors, since 30 their only point of support is usually at their lower edge, and on account of the security of connection that is required, it is often necessary to employ unsightly and unwieldy means to that end, and further- 35 more, unless the fit is exceptionally snug or close, which is not desirable since it promotes sticking or binding, an annoying rattle is produced.

Accordingly, the present invention proposes a construction which will eliminate 40 many of the objections incident to present devices and provide a panel which may be positively, and at the same time, resiliently connected to the door, whereby it will be 45 placed under a tension at all times when the door is closed, thus eliminating the possibility of a rattle and insuring a neat and accurate fit.

A further object of the invention is to 50 provide a practical and commercial device which is substantial, reliable and easily applied without the services of a skilled mechanic.

With the above and other objects in view 55 which will more fully appear as the nature

of the invention is better understood the same consists in the novel construction, combination and arrangement of parts herein-after more fully described, illustrated and claimed.

60 A preferred and practical embodiment of the invention is shown in the accompanying drawings, in which:—

Figure 1 is a fragmentary elevation of an automobile body showing the door there- 65 of having a sash panel fitted thereto according to the present invention.

Fig. 2 is a vertical sectional view on the line 2—2 of Fig. 1 looking in the direction of the arrow, with the door closed, and the 70 sash panel under tension.

Fig. 3 is a view similar to Fig. 2, showing in a somewhat diagrammatic fashion, the door open and about to engage the door frame, with the sash panel free from ten- 75 sion.

Fig. 4 is a detail side elevation partly in section, showing the relative position of parts of the present invention before en- 80 gagement.

Fig. 5 is a front elevation of the construction shown in Fig. 4, the dotted lines indicating the position of the sash element when it is engaged with the top of the door.

Fig. 6 is a detail perspective view show- 85 ing more clearly the spring socket of the present invention, and the preengagement position of the tongue or tenon carried by the sash.

Fig. 7 is a detail perspective view showing 90 the top of the door, and a closure plug which may be inserted in the opening in the top edge of the door, to provide a more finished appearance for the upper edge of the door when the sash is not carried thereby.

95 Similar references designate corresponding parts throughout the several figures of the drawings.

While the present invention is susceptible of application to various types and designs 100 of side panel construction for forming convertible open and closed auto bodies, for the purposes of illustration the vehicle body shown in the drawings is preferably of the type having the body portion B, door D and 105 a permanent top T, which is formed along the side thereof with a suitable recessed or rabbeted portion R which provides an abutment-seat for receiving the upper or top frame members of the sash panels. Accord¹ 110

ingly, in carrying the present invention into effect, it is proposed to employ a sash panel element 1 of suitable design having the frame work 2 and glass 3 and which is 5 adapted to fit in the doorway of the automobile body above the space occupied by the swinging door, which permits entrance to the car body, to provide a closure for the full length of the doorway.

- 10 As will be observed from the drawing the door D preferably comprises the opposite side frame members 7 and the top member 8, which latter is provided on its upper face with a longitudinally extending bead 9, in- 15 tended to coöperate with the corresponding groove 10 in the lower edge of the bottom rail of the sash frame 2, to provide a neat and closed joint between the sash and door, while at the same time constituting a pivot 20 or fulcrum bearing on which the entire sash may slightly rock or tilt, as will herein- after more fully appear.

With further reference to the door D it will be observed that the side frames 7 there- 25 of each carry near their upper corners a tenon receiving and holding keeper socket 11, the mouth M of which is preferably located in relatively close proximity to the lower edge of the top frame piece 8 of the 30 door in communication with the wide end of a flaring clearance opening 12 extending through the frame piece 8. This opening or clearance is provided at the entrance with an escutcheon plate 13 having therein a rela- 35 tively narrow longitudinally disposed entrance slot 14 for receiving the flat rigid tongue or tenon element 15, formed with an attaching bracket 16. These brackets are carried by each corner of the sash and pref- 40 erably include an angular securing portion 17 as shown in Figs. 1 and 5, which may be fastened by screws 18 or their equivalent to both the horizontal and upright frame mem- 45 bers of the sash to rigidly hold the bracket in place.

As previously stated the said tenon 15 is preferably flat and of relatively stout rigid metal, and is provided on one face near its lower extremity with a transverse holding 50 notch 19. Further, the cross sectional dimensions of the tongue are substantially the same as the slot 14, enough play however being present to prevent binding and permit the tongue to freely enter and withdraw from 55 the slot. Thus at this point it may be noted that because of this fit and the rockable bearing of the sash on the beading 9, the entire panel is pivotally connected or hinged to the door. The entrance of the tenon 15 into the 60 slot 14 and flared clearance 12, of course, prevents displacement of the sash from the upper edge of the door but permits the same to rock on the beading 9, and this rocking or tilting of the sash is controlled by limiting 65 the freedom of movement of the free end of

the tongue or tenon 15, by spring tension, whereby when the door is open or away from the jamb the free end of the tongue will be automatically pushed in such a direction that the upper edge of the sash will tilt in- 70 wardly toward the door jamb and away from the perpendicular as shown in Fig. 3.

Referring now to the means for accom- plishing this end, it will be observed that the socket element 11 previously referred to 75 preferably comprises an angular body plate 20, one flange 21 of which may be secured to the door frame by the fastenings 22 while the other flange 23 thereof constitutes a guard and abutment for the tongue 15. The 80 attaching flange 21 of the said plate element 20 is preferably formed at its upper edge with an offset attaching ear 24 which lies in a plane at right-angles to the flange 21, and parallel with the flange 23, and carries a stout tenon engaging and deflecting leaf- 85 spring 25 by means of a bolt 26 or the like as clearly shown in Fig. 6 of the drawings. The body of said spring 25, thus being rigidly attached to the ear 24, occupies a position 90 substantially parallel to the flange 20, thereby providing a tenon clearance or socket S. However, the lower end of the spring is pro- 95 vided with a convex tenon-engaging hook H the rounded side of which normally extends over into close proximity to the inner sur- face of the flange 23 to practically close the lower end of the socket S.

Thus when the tenon 15 is inserted in said 100 socket it will move substantially parallel to the body of the spring 25 until it comes in contact with the hook H when it will be deflected into engagement with the abutment flange 23 and the rounded portion of said hook engages the transverse notch 19. That 105 is to say, when the tongue 15 is inserted in the socket S, the spring 25 will push the free end thereof into engagement with the guard flange 23, which flange, as will be observed from Figs. 2, 3, and 4, is located at one side 110 of a perpendicular plane coincident with the outer edge 14^a of the slot 14. Accord- 115 ingly, since the tongue is rigidly carried by the sash, and the sash is capable of rocking or tilting on the bead, 9, the top edge thereof will be tilted or canted inwardly toward the door jamb if the door is open as shown in Fig. 3. However, when the door is closed, so that the top frame member of the panel 1 fits in the rabbeted seat 5, the entire panel 120 will be rocked on the bead 9 into a vertical position as shown in Fig. 2 against the ten- 125 sion of the spring 25. That is to say, in being pushed into a vertical position, by the closing of the door, the entire sash is held seated against the tension of the spring 25, as will be observed from Fig. 2, wherein the rigid tongue 25 is shown as being out of contact with the guard flange 23, and firmly 130 engaged with the rounded outer surface of

the convexed portion of the spring. Therefore, since the frame 2 of the panel is held seated under the tension of the spring 25, any tendency thereof to rattle is entirely 6 eliminated.

For the purpose of concealing the slot 14 when the panel 1 is removed to provide an open body, there is preferably employed a closure plug 27 which comprises the spring 10 retaining arms 28 and a bead-like head portion 29 similar in shape to the bead or molding 9 on the top edge of the door. Fig. 7 of the drawings shows this plug in perspective above the slot 14, and it will, of course, 15 be understood that when the plug is inserted in the slot the latter is entirely closed, and the bead portion 29 thereof cooperates with the bead or molding 9 to form a substantially unbroken surface.

From the foregoing, it will be apparent that one of the distinctive features of the present invention is the provision of a yieldable connection between the sash panel and the door, which can be easily and quickly 20 established, and at the same time eliminate all possibility of rattle when the door is closed. By way of forming this yieldable connection it may be noted that when the sash is put in place on the top of the door, 25 each tenon element 15 carried thereby enters one of the slots 14, which is slightly at one side of the center of the escutcheon plate 13, and moves downwardly in a substantially perpendicular plane along the vertical inner 30 face of the spring 25 as indicated in Fig. 4. The sash panel 1 may, therefore, assume a vertical position during the greater part of its movement toward the top of the door, but upon reaching the rounded side of the 35 convexed holding hook 24, the end of the tenon becomes deflected against the face of the guard flange 23, as also indicated by dotted lines in Fig. 4. This forcing of the free end of the tongue 15 by the spring 25 40 into engagement with the wall 23, which as previously stated is located at one side of the outer edge 14^a of the slot, thus causes the entire sash to tilt inwardly on the bead 9 and edge 14^a of the slot 14 toward the 45 door jamb, assuming of course that the door is open when the sash is applied thereto. Accordingly, it will be apparent that the 50 said outer edges 14^a of the slots constitute a fixed fulcrum for the tenons 15 to tilt or 55 cant to the sash, while the inner edges 14^b of the slots lie in substantially the same perpendicular plane as the inner vertical face 25^a of the spring.

Owing to the relatively off-center position 60 of the slot 14 with relation to the socket 8, and the position of the rounded nose of the convexed holding portion 24 of the spring 25, the entire sash is given an inward tilt 65 away from the vertical as clearly shown in Fig. 8 of the drawings. When the door is

closed the upper edge of the sash or frame 1 will abut with the shoulder provided by the rabbeted seat R in the top T of the automobile body, and when the upper edge of the sash panel strikes this abutment, it will 70 be forced outwardly against spring tension to the position shown in Fig. 2 of the drawings. All of the greatest swinging movement or play of the sash takes place at the upper free end thereof, while the lower edge 75 having the groove 10 therein rocks on the beading or molding 9. Furthermore, owing to the relatively large dimensions of the clearance slot 12 beneath the entrance slot 14, the rocking movement of the sash on the beading 9 is not hindered, and the spring 25 in each element 11 is relatively free to exert its full influence on the free end of the tenons 15. When the sash is seated on the door 80 and the free end of the tongue 15 is forced into frictional contact with the inner face of the guard flange 23, the holding of the sash in position is assisted by the engagement of the rounded surface of the hooked portion 24 of the spring 25 engaging with 85 the notch 19 of the tongue, thus preventing accidental displacement.

Without further description, it is thought that the many features and advantages of the present invention will be readily apparent, and it will be understood that various changes in the form, proportion and minor details of construction may be resorted to without departing from the spirit of the invention or scope of the appended claims. 90

I claim:

1. A door construction for convertible automobile bodies comprising in combination, a door case and a door permanently hinged thereto, a removable and replaceable sash panel adapted to have a rockable bearing engagement with the upper edge of the door and carrying tenon elements therewith, a socket device permanently carried by the door for each tenon and having a locking 105 and deflecting spring engaging the lower end of said tenon elements only when the sash is on the door to place the said tenons under tension and tilt the sash panel toward the door case. 110

2. A door construction for convertible automobile bodies comprising in combination, a door case, a swinging door permanently hinged to said case and including a frame having slots in the top member thereof, yielding tenon engaging and deflecting means carried by the door frame below said slots, and a removable and replaceable panel having tenon means at each corner for entering said slots and detachably engaging 120 with said tenon engaging and deflecting means to tilt the door inwardly against one edge of said slots. 125

3. A door construction for convertible automobile bodies comprising in combina- 130

1. **4** 1. A fixed top having an abutment-seat, a door permanently hinged to said body and including a frame having slots in its top member, socket means including a deflecting spring carried by the side frames of the door below the upper edge thereof and in communication with said slots, and a detachable sash panel having a tenon carried by each corner thereof for entering the slots in the frame of the door to prevent displacement and also to engage with the spring in the socket means only when the panel is placed on the door to tilt the upper edge of the panel toward the abutment-seat of the fixed top.
2. A panel attachment for vehicle bodies comprising in combination, a vehicle body having a panel seat, a fulcrum bead, a sash panel separate from said bead and adapted to be engaged and disengaged therefrom by a substantially vertical movement, and means located below said bead for detachably and yieldably engaging a portion of said panel when the same is on the fulcrum bead to rock the same toward its seat.
3. A door construction for convertible automobile bodies comprising in combination with a swinging door including a frame and a fixed top having an abutment-seat, of a removable sash panel having a groove in its lower edge, tenon elements carried by the lower corners of the sash panel, a bead carried by the upper edge of the door frame for fitting in said groove in the lower edge of the sash panel, the said portion of the door frame carrying the bead having slots, socket elements carried by the side frame portions of the door near the upper edge thereof and communicating with said slots, said socket elements including resilient means for engaging and deflecting the free end of the said tenon elements carried by the sash panel when the latter is mounted on top of the door.
4. A door construction for convertible automobile bodies comprising in combination with a swinging door including a frame and a fixed top having an abutment-seat, of a removable sash panel also including a frame having a groove in its lower edge, tenon elements having a bracket portion attached to the frame of the sash panel, a bead carried by the upper face of the horizontal top member of the door frame, said latter member having longitudinally disposed slots therein located at one side of the center thereof, spring socket elements carried by each of the side frame members of the door and having their entrance ends in close proximity to said slots, said socket elements including a tenon engaging and deflecting spring having the body portion thereof substantially in alignment with the inner edge of the slot in the door frame.
5. A door construction for convertible automobile bodies comprising in combination with a swinging door including a frame and a fixed top having an abutment-seat, of a removable sash panel rockably mounted on the upper edge of the door, tenon elements depending from each corner of said sash panel, and socket elements carried by the side frame members of the door and having their entrance end in communication with a slot in the top frame piece of the door, said socket elements each including an abutment flange, and a tenon engaging and deflecting spring co-operating to form a tenon receiving socket, said spring having the body portion thereof substantially parallel with the abutment flange, and having a curved holding hook portion at its lower end which normally extends over into close proximity to the abutment flange to practically close the socket portion, said spring being adapted to engage and deflect the lower end of the tenon elements carried by the sash panel to tilt the latter toward the abutment-seat of the fixed top.
6. A door construction for convertible automobile bodies comprising in combination with a swinging door including a frame and a fixed top having an abutment seat of a removable sash panel rockably mounted on the upper edge of the door, tenon elements depending from each corner of said sash panel, and socket elements carried by the side frame members of the door and having their entrance end in communication with a slot in the top frame pieces of the door, said socket elements each consisting of an angular body portion having an attaching flange and a right-angularly disposed abutment flange, and a supporting ear formed from said attaching flange and spaced from the abutment flange, a tenon engaging and deflecting spring carried by said ear and having the body portion thereof substantially parallel with the inner face of the abutment flange to provide a socket portion, and having a rounded hook portion at its lower end which extends into close proximity to the inner surface of the abutment flange to substantially close the socket to thereby engage and deflect the free end of the tenon element carried by the sash panel to tilt the latter toward the abutment-seat of the fixed top.
7. A door construction for convertible automobile bodies comprising in combination with a swinging door including a frame and a fixed top having an abutment-seat, of a removable sash panel rockably mounted on the upper edge of the door, tenon elements rigidly carried by each corner of the sash panel and depending therefrom, socket elements carried by the side frame members of the door having their entrance end in communication with the wide end of a flared clearance opening in the top frame piece of

the door, an escutcheon plate for said opening having a slot arranged at one side of the vertical axis of the socket element, a tenon engaging and deflecting spring carried by 5 the socket element and having the body portion thereof lying in a plane substantially coincident with the inner edge of the slot in the escutcheon plate, and having a curved holding end an abutment flange extending 10 throughout the length of the socket element and arranged substantially parallel with the body of the spring to form a tenon receiving socket, said spring deflecting and clamping the lower end of the tenon element carried 15 by the sash panel between itself and said abutment flange.

10. A door construction for convertible automobile bodies comprising the combination with a door frame and a swinging door, 20 of a removable sash panel rockably mounted on the upper edge of the door, tenon elements carried by said sash panel, escutcheon plates carried by the door for receiving said tenon elements, and spring means carried by

the door below said escutcheon plate for deflecting and holding said tenon elements, 25 said spring means in deflecting the tenon elements utilizing one edge of the slot in the escutcheon plate as a fulcrum.

11. A door construction for convertible 30 automobile bodies comprising the combination with a door frame of a swinging door including a frame having slots in the top member thereof, an upstanding bead also on the latter, yielding tenon clamping and deflecting means carried by the door below 35 said slots, a sash panel having a groove for rockably receiving said bead and tenons carried by said panel for entering said slots, and engaging with said yielding tenon clamping 40 and deflecting means.

In testimony whereof I hereunto affix my signature in the presence of two witnesses.

CHARLES REDECKER.
